UNDERWATER TOWING VEHICLE

George J. Peroni, Miami, Fla., assignor to
Seatech Corporation, Miami, Fla.

Filed July 13, 1970, Ser. No. 23,930

Term of patent 14 years

Int. Cl. D21—02

U.S. Cl. D71—1

FIG. 1 is a side view of the underwater towing vehicle showing my new design, the opposite side having substantially the same appearance;

FIG. 2 is a front view of the vehicle shown in FIG. 1 and illustrating the driving propeller;

FIG. 3 is a rear view of the vehicle shown in FIG. 1 and illustrating the rear closure dome;

FIG. 4 is a top view of the vehicle shown in FIGS. 1-3;

FIG. 5 is a bottom plan view of the vehicle shown in the preceding figures; and

FIG. 6 is the perspective view of the same.

I claim:

The ornamental design for an underwater towing vehicle, as shown and described.
